UNITED STATES PATENT OFFICE.

LULU VERHOREN LAVELL, OF MINNEAPOLIS, MINNESOTA.

DESIGN FOR A CARD-TABLE MARKER.

Application filed May 26, 1927. Serial No. 22,165. Term of patent 3½ years.

To all whom it may concern:

Be it known that I, LULU VERHOREN LAVELL, a citizen of the United States, residing at Minneapolis, in the county of Hennepin and State of Minnesota, have invented a new, original, and ornamental Design for Card-Table Markers, of which the following is a specification, reference being had to the accompanying drawing, forming part thereof.

The figures are I, a plan view and II, a side view of a card table marker, showing my new design.

I claim:

The ornamental design for a card table marker as shown.

LULU VERHOREN LAVELL.
